CLAIM

The ornamental design for a pet water fountain, as shown and described.

DESCRIPTION

FIG. 1 is a front elevational view of a pet water fountain showing my new design;
FIG. 2 is a rear elevation view thereof;
FIG. 3 is a left side view thereof;
FIG. 4 is a right side view thereof;
FIG. 5 is a top plan view thereof;
FIG. 6 is a bottom plan view thereof;
FIG. 7 is a first perspective view thereof;
FIG. 8 is a second perspective view thereof; and,
FIG. 9 is an enlarged view of portion 9 in FIG. 7.

(Continued)

The broken lines in the drawings illustrate portions of the pet water fountain which form no part of the claimed design.

1 Claim, 9 Drawing Sheets
